UNITED STATES PATENT OFFICE.

BENJAMIN F. CAYFORD, OF SKOWHEGAN, MAINE.

OVERDRAW-BRIDLE.

Specification of Letters Patent. Patented Oct. 19, 1915.

1,157,207.

Application filed November 30, 1914. Serial No. 874,816.

To all whom it may concern:

Be it known that I, BENJAMIN F. CAYFORD, a citizen of the United States, residing at Skowhegan, in the county of Somerset and State of Maine, have invented certain new and useful Improvements in Overdraw Bridles; and I do hereby declare the following to be a full, clear, and exact description of the invention, such as will enable others skilled in the art to which it appertains to make and use the same.

This invention relates to bridles and in particular to horse bridles of the over draw type.

The principal object of this invention is to provide a bridle so constructed that the mouth of the horse will be held forward to permit of ready breathing.

Another object of this invention is to provide a bridle so constructed that the horse may rest his jaws upon the under draw strap.

With these objects in view, the invention consists of the improved construction arrangement and combination of the parts of a bridle which will be hereinafter fully described and afterwards specifically claimed.

I have illustrated a preferred embodiment of the invention in the accompanying drawings, in which,

Figure 1 represents a view of the bridle in side elevation, in position upon a horse, and Fig. 2, a perspective view of the bridle removed from the horse.

In the drawings, 1 indicates the crown piece adapted to encircle the head of the horse behind the ears as is customary in bridles, and 2 the brow band of the usual form, said brow band being connected at 3 to the crown piece 1. Running under the neck of the horse is the throat latch 4 likewise connected at 3. Running from the connecting point 3 are the cheek straps 5, the lower ends of which are connected to the rings of the bit 7 being passed therethrough and buckled to said cheek straps, forming loops 8, one being shown in Fig. 1. The bit 7 is of the usual form, having the knobbed bar 7 with the ring 6 passing through the end, as is the usual form of such bits. An under draw strap 9 is adapted to pass through the loops 8, the two branches of the strap being passed through looped keepers 10 at the ends of the nose band 10, after which they are continued along the ridge of the horses' head and passed through a slid-

ingly mounted runner 11, thence through keepers 12 and 13 on the crown piece 1, to the forward end of the check rein 14 to which the ends are adjustably secured by 60 means of buckles 15 or other suitable forms of fastening devices. A short over draw strap 16 is buckled at one end, at 17, to the crown piece 1 and passes through the runner 11 to which it is secured down to the central portion of the nose band 10 where it is fastened in a manner to hold the same in proper position, as illustrated in Fig. 2 of the drawings. An over draw bit 18 projects through guides 10^b formed in the nose band 70 10 as indicated in Fig. 2 of the drawings so that said nose band is securely fastened to said over draw bit 18. The over draw bit 18 is preferably formed of metal, having the upper portion thereof elongated and approximately narrow in form thereby forming a loop, and the lower portion thereof widened and curved downwardly as at 19, the curved portions 19 being connected by a cross bar 20 which is slightly curved inwardly and upwardly at 21 to conform somewhat with the interior of the upper jaw of the horse 22, said portions 19 passing over the exterior surface of the upper jaw and within and across the mouth of the horse 85 adjacent the bit 7 thereof in such manner that the portion 21 will project toward the roof of the mouth. The upper elongated looped portion of the over draw bit 18 has secured thereto an over draw check strap 90 23, the opposite end of which is suitably connected to the check rein 14 by means of adjustable buckle connections 24 or other suitable forms of fastening devices. By this arrangement the over draw bit can be adjusted to suit the size of the horse upon which it is intended to be used in such a manner that the horse's head is retained forwardly to permit the ready breathing of the animal, the strain of this operation being 95 transmitted through the over draw check strap 23. It is also to be noted that by the adjustable construction of the bridle the under draw strap 9 will permit the horse to rest his jaw thereupon and yet retain the 100 horse's head in a forwardly extending position.

To prevent the jaws of the horse from being forced open unduly, a strap band 25 is connected at its ends to the nose band 10 110 and is adapted to encircle the jaws of the horse, being fastened therefore by means

of an adjustable buckle fastening device 26, as plainly shown in Fig. 2. This last mentioned construction eases the horse should he pull hard and bear down upon the

5 over draw bit of the bridle, as the jaws would otherwise tend to be forced open, which act is prevented by this last mentioned strap band 25. If desired, a reinforcing or retaining strap (not shown) can be mounted between the strap band 25 and the throat latch strap 4 thereby running under the lower portion of the jaws of the horse.

This bridle construction is particularly adapted for race horses and hard mouth 15 horses or horses commonly known as pullers, and is so constructed as to readily retain the strain of operation without inconvenience or discomfort to the horse upon which the bridle is mounted.

20 The form herein shown and described is the preferred embodiment of the invention, but the right is expressly reserved to make such alterations and variations therein from time to time as it may be deemed expedient, and which will neither depart from the spirit 25 of the invention nor the scope of the claims.

Having now described my invention, what I claim as new and desire to secure by Letters-Patent, is:—

30 1. A bridle comprising a crown piece, brow bands, check rein, cheek straps, and a bit connected with the cheek straps, a nose band provided with guides and keepers, an over draw bit projecting through the guides, 35 an under draw strap projecting through the keepers and having branches connected with the check rein, and means for holding the branches of the under draw strap slidably connected with the crown piece.

40 2. A bridle comprising a crown piece, brow band, check rein, cheek straps, and a bit connected with the cheek straps, a nose band provided with guides and keepers, an over draw bit projecting through the guides,

45 an under draw strap projecting through the keepers and having branches connected with the check rein, means for holding the branches of the under draw strap slidably connected with the crown piece, and an over draw strap adjustably connecting the nose band and crown piece.

50 Copies of this patent may be obtained for five cents each, by addressing the "Commissioner of Patents, Washington, D. C."

3. A bridle comprising a crown piece, brow band, check rein, cheek straps, and a bit connected with the cheek straps, a nose band provided with guides and keepers, an over draw bit projecting through the guides, 55 an under draw strap projecting through the keepers and having branches connected with the check rein, means for holding the branches of the under draw strap slidably connected with the crown piece, an over draw strap adjustably connecting the nose band and crown piece, and an adjustable jaw holding strap connected with the ends of the nose band.

4. A bridle comprising a crown piece, a brow strap, a check rein, a throat latch strap, the ends of said straps being connected together, a bit, cheek straps connected at their upper ends to said connecting points of said strap and looped through said bit at their lower portions, the looped ends of said jaw straps being buckled to the cheek straps, an under draw strap mounted between said looped portions of said cheek 75 strap and running under the jaws of a horse, an overdraw bit having an elongated upper portion thereto, a nose band mounted upon said over draw bit and supporting said under draw strap, an adjustable strap 80 mounted upon said nose band strap and adapted to encircle the jaws of a horse to retain them closed, adjustable means to connect the upper ends of said under draw strap to a check rein, and an over draw 85 check strap connected at one end to the upper looped portion of said over draw bit at one end and adjustably connected to a check rein at its other end, said bridle being adapted to retain the mouth of a horse forwardly and upwardly to support the mouth 90 of a horse in such retained position and to prevent the undue opening of the mouth of the horse while so retained.

In testimony whereof I have signed my 95 name to this specification in the presence of two subscribing witnesses.

BENJAMIN F. CAYFORD.
